CABINET

Wilbert E. Theobald, Peru, Ind., assignor to
 Standard Cabinet Manufacturing Company,
 Inc., Peru, Ind., a corporation of Indiana

Application February 6, 1952, Serial No. 270,164

6 Claims. (Cl. 312—276)

1

This invention relates to an article of furniture of the cabinet type for enclosing an apparatus, such, for example, as an ironer, a sewing machine, or any other device.

As such, an object of the invention is to provide in such cabinet a stationary working table or partition on which the apparatus is mounted and to associate with this partition side wall sections which, upon movement of a top wall to a position extensive with the back wall of the cabinet, are moved into a position extensive with the work table or partition, thereby to provide working shelves automatically movable from and into closed position upon opening and closing movement of the top wall of the cabinet.

Another and equally important object of the invention is the provision of a cabinet having, in addition to the features above referred to, a lower compartment which may have confined therein shelves or drawers and which will provide a space for the needs of the operator when the cabinet is arranged with its parts in closed position for working or operating purposes of the apparatus mounted upon the work table or partition.

Yet another and equally important object of the invention is to provide a cabinet having in addition to the above features an exterior dressing which will provide, when the cabinet is in closed condition, a neat and pleasing appearance.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention;

Fig. 2 is a perspective rear view of the cabinet shown in Fig. 1 illustrating certain parts thereof in partially extended position;

Fig. 3 is a fragmentary perspective view of a corner portion of the cabinet illustrated in Fig. 1, looking from the rear thereof;

Fig. 4 is a fragmentary perspective view of such corner, showing certain parts thereof in extended position;

Fig. 5 is a fragmentary sectional detail view taken substantially on line 5—5 of Fig. 3;

Fig. 6 is a fragmentary sectional detail view taken substantially on line 6—6 of Fig. 4.

I prefer to accomplish the several objects of my invention by the preferred form of construction which I have illustrated in the accompanying drawings. In this connection the article of

2

furniture embodying my invention comprises a cabinet 10 having a back wall 11, side walls 12, a front wall 13, and a top wall 14.

The cabinet 10 is divided into an upper compartment 15 and a lower compartment 16. The lower compartment may have arranged therein along the opposite side walls 12, shelves or drawers, leaving the central or middle portion of the compartment unobstructed for the accommodation of the knees of a person sitting in front of the cabinet 10 when the parts of the cabinet to be presently described are in extended condition.

The upper and lower compartments 15 and 16 are separated by a work table or partition 17 secured in any suitable manner to the back wall 11 and to the side walls 12. On this table 17 may be arranged an apparatus such as an ironing mechanism, sewing machine, or the like.

The front wall is divided into an upper portion 18 and a lower portion 19, the lower portion 19 of the front wall 13 comprising two doors 20 hinged as at 21 to the side walls 12. The upper portion 18 of the front wall is hinged along its top edge 22 by means of hinges 23 to one edge 25 of the top wall 14. This upper section is provided with handles 25' which facilitate manipulating the upper portion 18 of the front wall 13 when the parts of the cabinet are in extended position. The top wall at its edge 25 opposite the edge 24 is hinged as at 26 to the top edge of the back wall 11.

Slide plates 27 are arranged in elongated slots 28 formed in the back wall 11. As shown the longitudinal edges of these slide plates project into grooves 27' provided by the back wall 11. These slide plates are of a length less than the length of the slots 28 for reasons to be presently understood. Elongated links 29 pivotally connect the top wall 14 to the top portion of the slide plates 27. These link members have lateral extensions 30 providing bolt openings 31.

The side walls 12 have upper portions or sections 32 which are hinged as at 33 to the work table 17. These side sections 32 have corresponding edge portions by means of arms 34 connected through slot and pin connections 35 to the lower edge portions 36 of the slide plates 27.

Spring members 37 are provided, and these spring members are associated with the arms 34 in a manner such that they function to maintain the side wall sections 32 either in closed or extended position with respect to the table 17.

To complete the invention, I provide latchbolts 38 which are carried by the top wall 14. These latch bolts 38 are normally forced away from

each other by means of a spring 39 arranged between the bearings 40 which provide connection between the bolts and the top 14. The rounded end portions 41 of these bolts are adapted to project into the bolt openings 31 when the top 14 is in extended position with respect to the back wall 11.

To arrange the parts in extended position by moving the top wall 14 about its hinge connection 26 with the back wall 11, the links 29 during such movement will act upon the slide plates 27, moving the slide plates upwardly in their respective slots 28. Simultaneously with this movement of the slide plates, the side wall sections 32 will be pivoted upwardly and downwardly about their hinged connections 33 with the work table 17.

The arrangement is such that when the top wall 17 is arranged in extensive relation with the back wall 11, the work table 17 will be exposed and the side wall sections 32 will be disposed in an extensive relation with respect to the work table 17, thereby providing working extensions of the table 17. The operator by opening the doors 20 may position herself comfortably close to the cabinet to perform work by means of the apparatus positioned on the work table 17. In such position, her knees will find accommodation within the lower compartment 16.

To move the parts into closed position with respect to each other, the operator disengages the bolts 38 from the link connection 29 by moving the bolts 38 toward each other, there being provided for this purpose finger extensions 38'. These bolts 38 by reason of their rounded heads 41 automatically are projected by the springs 39 into the openings 31 as and when such openings are moved into alignment with such bolts.

While I have shown one form of latching the extended parts in one position, it is clearly obvious that other forms may be applied without departing from the invention.

From the foregoing description, it will be obvious that I have provided an article of furniture which will be highly useful for the purposes herein contemplated and which when in closed position will provide an article of furniture which has an appearance pleasing to the eye.

The article of furniture comprises relatively few parts, thereby enabling economical manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall for said movement, means for hinging the upper

front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sections, means for hinging the upper of said sections to the side edge portions of said partition, and means providing connection between said upper sections and said slide members, whereby said upper sections will pivot about their hinge connection with said partition by movement of said slide members when the latter are moved relative to said back wall by movement of said top wall.

2. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall for said movement, means for hinging the upper front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sections, means for hinging the upper of said sections to the side edge portions of said partition, and means providing connection between said upper sections and said slide members, whereby said upper sections will pivot about their hinge connection with said partition by movement of said slide members when the latter are moved relative to said back wall by movement of said top wall.

3. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall for said movement, means for hinging the upper front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sections, means for hinging the upper of said sections to the side edge portions of said partition, and means providing connection between said upper sections and said slide members, whereby said upper sections will pivot about their hinge connection

with said partition by movement of said slide members when the latter are moved relative to said back wall by movement of said top wall, and latch means for releasably latching said top wall in said extensive position with respect to said back wall.

4. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall for said movement, means for hinging the upper front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sections, means for hinging the upper of said sections to the side edge portions of said partition, means providing connection between said upper sections and said slide members, whereby said upper sections will pivot about their hinge connection with said partition by movement of said slide members when the latter are moved relative to said back wall by movement of said top wall, spring means acting on said upper sections to hold said upper sections in either their extended or closed position relative to said partition, and latch means for releasably latching said top wall in said extensive position with respect to said back wall.

5. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall for said movement, means for hinging the upper front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sec- 60

tions, means for hinging the upper of said sections to the side edge portions of said partition, and means providing connection between said upper sections and said slide members, 5 whereby said upper sections will pivot about their hinge connection with said partition by movement of said slide members when the latter are moved relative to said back wall by movement of said top wall, said link connections providing latchbolt openings midway between their end portions, and latchbolts carried by said top wall and adapted for engagement with said bolt openings when said top wall is disposed in said extensive position with respect to said back wall.

10 6. An article of furniture comprising a cabinet, a stationary partition arranged in said cabinet in a substantially horizontal plane and dividing the same into an upper and lower compartment, said cabinet having a front wall divided into sections, a top wall normally disposed in a substantially horizontal plane and movable from said plane to a position extensive with the back wall of the cabinet, means for hinging the top wall at one edge thereof to the back wall 15 for said movement, means for hinging the upper front wall section to an edge of the top wall opposite said one edge, a pair of slide members carried by the back wall for vertical movement relative thereto, link connections between the slide members and said top wall for moving the slide members relative to the back wall when said top wall is moved to said extensive position with said back wall, said cabinet having side walls divided into upper and lower sections, 20 means for hinging the upper of said sections to the side edge portions of said partition, means providing connection between said upper sections and said slide members, whereby said upper sections will pivot about their hinge connection 25 with said partition by movement of said slide members when the latter are moved relative to said back wall by movement of said top wall, and spring means acting on said upper sections to hold said upper sections in either their extended or closed position relative to said partition, said link connections providing latchbolt openings 30 midway between their end portions, and latch bolts carried by said top wall and adapted for engagement with said bolt openings when said top wall is disposed in said extensive position with respect to said back wall.
